ENGINE STARTER

Leslie Aubrey Morrison, Pampa, Tex., assignor to
Morrison Starter Company, Pampa, Tex., a cor-
poration of Texas

Application June 15, 1950, Serial No. 168,245

1 Claim. (Cl. 74—6)

1

This invention relates to an engine starter and, more particularly, to a starter which includes a pneumatic motor adapted to operate on low gas pressures and which starter is particularly adapted for use with gas engines and gasoline engines.

It has been proposed heretofore to employ starters which include pneumatic motors but require high gas pressures for starting gas engines and the like. Such starters have not proved to be practical because of the high gas pressures required and the fact that such high gas pressures are not readily available particularly in oil fields and the like. Also, the starters heretofore proposed employ gears, usually complicated gear trains. The type of starter most commonly employed prior to my invention has involved a pneumatic motor connected by a gear train to a ring gear attached to the flywheel of the engine. All of such engine starters are complicated in construction and expensive. In general, they will not withstand the loads involved and the gears tend to break, particularly when the engine backfires. In the starters most commonly employed, the pneumatic motor is closely associated with the gear train, and gas from the motor tends to escape into the gear train resulting in frequent explosions, due to the sparks generated by the gear train, damaging the starter and the engine and constituting a very decided hazard to the operator.

It is an object of my invention to provide a simple and inexpensive engine starter which does not have the objectionable features of the starters of the prior art. Another object is to provide a starter which is particularly adapted for use with gas engines and gasoline engines and especially for oil field pumping engines. A further object is to provide an engine starter which includes a pneumatic motor and which is adapted to operate on low gas pressures that are readily available particularly in oil fields. A particular object is to provide an engine starter which does not employ gears, which is more dependable in operation, which will better withstand the loads involved without breaking of the parts particularly when engine backfires, and which is less hazardous to use. A still further object is to provide an engine starter which can be repaired more easily and economically. Still another object is to advance the art. Other objects will appear herein-after.

The above and other objects may be accomplished in accord with my invention wherein I provide an engine starter which comprises a pneumatic motor which is adapted to operate on

2

a gas pressure of from about 12 to about 35 pounds per square inch, a driving pulley on the shaft of the motor, a driven pulley spaced from the driving pulley and having a diameter about 3 to about 20 times the diameter of the driving pulley, a belt operatively connecting the pulleys, a longitudinally movable elongated starter shaft extending through the center of the driven pulley and secured to such pulley for rotation therewith, bearings for the starter shaft spaced from the ends of the starter shaft and slidably supporting the starter shaft, a crank nut engaging member on one end of the starter shaft adapted to releasably engage a crank nut on the end of an engine shaft, and a spring associated with the starter shaft normally forcing the starter shaft to a retracted position with the crank nut engaging member disengaged from the crank nut.

In order to start an engine with my starter, the engine and starter are positioned so that the starter shaft is in alignment with the engine shaft and the crank nut engaging member on the end of the starter shaft is near the crank nut on the end of the engine crank shaft. The starter shaft is pushed manually so that it slides longitudinally in its bearings until the crank nut engaging member engages the crank nut. The pneumatic motor is then operated and, through the pulleys and belt, turn the starter shaft to start the engine. When the engine starts firing and is running, the crank nut engaging member automatically disengages from the crank nut and the starter shaft is automatically returned to its normal retracted inoperative position with the crank nut engaging member out of contact with the crank nut.

My invention and its mode of operation will be more readily understood from the following more detailed description taken with the accompanying drawings, which illustrate preferred embodiments of my invention, in which:

Figure 1 is a perspective view of the engine starter, shown in position for operating an engine, and

Figure 2 is an enlarged vertical sectional view, taken through the center of the driven pulley, illustrating one type of structure permitting longitudinal motion of the starter shaft.

Figure 3 is an enlarged vertical sectional view, taken through the center of the driven pulley, illustrating another type of structure permitting longitudinal motion of the starter shaft.

In the drawings, the numeral 10 designates the front end of an engine to be started provided with a crankshaft 12 and a crank nut 14 of conventional construction. As shown, the engine is

mounted on a skid 16, which is in the form of an I-beam, in a manner common with oil pumping engines. However, it will be understood that my starter may be employed with any type of gas engine or gasoline engine, either stationary or mobile, and it is not necessary that the engine be mounted on a skid.

The starter of my invention, as shown, is mounted on a bracket 18 secured to the skid 16 through key slots 20 and nuts and bolts, as shown. It will be apparent that the type of bracket may be widely varied and that it need not be fastened to a skid but may be fastened to any other desirable support or to the front end of the engine, as desired. A pneumatic motor 22 is mounted on the bracket 18 and is connected with a source of gaseous fluid under pressure through a throttling valve 24 and pipe 26 in the conventional manner. The pneumatic motor 22 is designed and adapted to operate under gas pressures of from about 12 to about 35 pounds per square inch. The gaseous fluid may be natural gas, air or steam. When the starter is to be employed where natural gas is readily available, as in oil fields, the gaseous fluid will usually be natural gas which is commonly under a pressure in the desired range.

A driving pulley 28 is secured to the shaft of the pneumatic motor 22 and is operatively connected with a driven pulley 30 by means of a belt 32. The driving pulley 28 may be from about 1 to about 10 inches in diameter, but, usually, will have a diameter of from about 2 to about 3 inches. The driven pulley 30 may have a diameter of from about 3 to about 30 inches, but, usually, will have a diameter of from about 18 to about 20 inches. The relative diameters of the pulleys will be dependent upon the size and type of the engine to be started and hence upon the load to be imposed upon the starter in starting the engine. The driven pulley should have a diameter of from about 3 to about 20 times the diameter of the driving pulley and, usually, from about 6 to about 10 times. The pulleys may be plain and the belt 32 may be flat. However, I generally prefer that the pulleys be sheaves and the belt a V-belt, as shown in the drawings.

The driven pulley 30 is provided with a hub 34. An elongated starter shaft 36 extends through the hub 34 and is secured to the pulley 30 so that it rotates with the pulley. As shown in Figure 2, the hub 34 is provided with a key 38. The shaft 36 is provided with an elongated keyway 40, extending longitudinally of the shaft, and which is slightly wider than the key 38 so as to permit the shaft 36 to be moved longitudinally relative to the pulley 30, the key 38 riding in the keyway 40. The shaft 36 is supported in bearings 42 in the upper end of the bracket 18. Such bearings are adjacent opposite sides of the pulley 30 and have their inner faces loosely engaging the end faces of the hub 34 to prevent lateral movement of the pulley while permitting rotation of the pulley relative thereto. The bearings 42 are slightly larger than the shaft 36 so as to permit longitudinal movement of the shaft relative to the bearings but preventing movement of the shaft in a direction perpendicular to its axis.

The shaft 36 is provided at one end with a crank nut engaging member 44 of conventional construction. As shown, the crank nut engaging member consists of two diametrically extending lugs which are adapted to engage in cooperating slots in the crank nut 14. It will be understood that the crank nut engaging means may

be widely varied as is common in the art and particularly in accord with the design of the particular crank nut on the engine crankshaft.

A spring retaining member 46 is secured to the other end of the shaft 36 and a spring 48 is positioned between the spring retaining member 46 and the bearing 42 nearest to the spring retaining member. Such spring retaining member may be a simple nut for engaging the end of the spring and maintaining it under the desired compression. However, as shown in the drawings, the spring retaining member 46 is in the form of a knob rotatably mounted on the end of the shaft 36 so that the operator may push on such knob to move the shaft 36 longitudinally and engage the crank engaging member with a crank nut, without having his hand come into contact with the rotating shaft. Such member 46 may be of any other design desired, such as a wheel or the like. Also, a spring retaining nut may be employed and a knob or other manually operable member may be rotatably mounted on the nut or on the end of the shaft beyond the end of the spring retaining nut.

The structure shown in Figure 2 may be further modified in the manner shown in Figure 3. In this modification, the pulley 30 and shaft 36 are immovably secured together by a key 38, but the bearings 42 are spaced apart by a distance equal to the desired longitudinal movement of the shaft 36. The pulley 30 moves laterally with the shaft when the shaft is moved longitudinally to engage the crank nut and to return to its normal position. In this modification, it is particularly desirable that the pulleys be in the form of sheaves connected by a V-belt.

In operation, the engine and the starter are positioned relative to each other so that the starter shaft 36 is in alignment with the engine 40 crank shaft 12, and the crank nut engaging member 44 is opposite the crank nut 14, but normally spaced therefrom. The operator manually pushes the shaft 36 longitudinally against the tension of the spring 48 until the crank nut engaging member 44 operatively engages the crank nut 14. The throttle valve 24 is then turned to operate the pneumatic motor 22 at the desired speed and, through the pulleys 28 and 30, belt 32 and shaft 36, to turn the engine at the desired speed to start it. When the engine starts and is running, the spring 48 will automatically retract the shaft 36 so that the crank nut engaging member 44 is automatically disengaged from the crank nut 14 and returned to its normal position out of contact with the crank nut.

It will be understood that the structures, specifically shown in the drawings and described in detail herein, constitute illustrative preferred embodiments of my invention and that my invention is not limited thereto. It will be readily apparent to those skilled in the art that many variations and modifications can be made in the details of construction without departing from the spirit or scope of my invention and I intend to claim my invention broadly as in the appended claim.

It will be apparent that the starter of my invention is simple and economical in construction. It is readily adaptable for starting engines of any desired type or size. It is dependable in operation and is composed of few and simple parts which may be readily and economically repaired or replaced. It withstands the loads required, including the loads and shocks involved when the engine backfires, and does

not contain gears, ratchets, diaphragms or like structures which tend to break or rapidly deteriorate. The pneumatic motor is not connected with the engine but is spaced therefrom so that there is no danger or explosions by gas leaking from the pneumatic motor into gear trains and the like. Therefore, it will be apparent that my invention constitutes a valuable advance in and contribution to the art.

The invention claimed is:

In an engine starter, a pneumatic motor designed and adapted to operate on a gas pressure of from about 12 to about 35 pounds per square inch, a driving sheave on the shaft of the motor having a diameter of from about 2 to about 3 inches, a driven pulley spaced from the driving sheave and having a diameter of from about 18 to about 20 inches, a belt operatively connecting the sheaves, an elongated starter shaft extending through the center of the driven sheave and immovably secured thereto, bearings slidably supporting the starter shaft opposite each side of the driven sheave, said bearings being spaced apart by a distance equal to the thickness of the sheave plus the distance between the crank

5 nut of the crankshaft of the engine to be started and the end of the starter shaft nearest to such crank nut and spaced from the ends of the starter shaft, a crank nut engaging member on one end of the starter shaft adapted to releasably engage a crank nut on the end of an engine shaft, and a spring associated with the starter shaft normally forcing the starter shaft to a retracted position with the crank nut engaging member disengaged from the crank nut.
